UNITED STATES PATENT OFFICE.

ARTHUR F. PRITSCHAU, OF DENVER, COLORADO.

NUT-LOCK.

SPECIFICATION forming part of Letters Patent No. 447,738, dated March 3, 1891.

Application filed June 7, 1890. Serial No. 354,569. (No model.)

To all whom it may concern:

Be it known that I, ARTHUR F. PRITSCHAU, of Denver, in the county of Arapahoe and State of Colorado, have invented certain new and

5 useful Improvements in Nut-Locks; and I do hereby declare the following to be a full, clear, and exact description of the invention, such as will enable others skilled in the art to which it appertains to make and use the same.

10 My invention relates to improvements in automatic nut-locks, the object of the same being to provide a device of the above character which may be put on the bolt with but little effort.

15 A further object is to provide a nut-lock offering uniform and firm resistance to the strain on the fish-plate.

A further object is to provide a nut-lock which when relaxing will not cut into the 20 nut, and one so constructed that its ends will not sink into the oval hole of the fish-plate.

25 A further object is to provide a nut-lock of the above character which will be simple and economical in construction and durable and efficient in use; and with these ends in view my invention consists in the certain features of construction and combinations of parts, as will be hereinafter fully described, and pointed out in the claim.

30 In the accompanying drawings, Figure 1 shows the nut-lock in position. Figs. 2 and 3 are end views of the lock, the former with shoulder and the latter without. Figs. 4, 5, 6, and 7 are side views of modified forms, and 35 Figs. 8 and 9 are perspective views of the preferred forms, Fig. 8 showing the condition of the lock before placed in position and Fig. 9 illustrating its position when on the bolt.

The lock is made of one piece of metal care- 40 fully tempered and of very strong tension.

The lock shown in Fig. 8 is made from a single piece of metal and is cut away on opposite sides thereof about one-fourth distance on each side of its center, starting with the 45 shoulders A and gradually tapering toward the ends, forming wedge-shaped sections B. The ends are coiled and are partially lapped one over the other, as shown, and are in strong frictional contact with the edges of each other 50 and form the bolt-hole C, which is adapted to embrace the bolt. When the lock is in position on the bolt, the two ends are forced together by means of tongs or other implement adapted thereto, making the bolt-hole oval, 55 and the wedges will slide together upon each

other, as shown in Fig. 9. When in position on the bolt, the point D touches on the flange of the rail, thereby preventing the lock from touching.

In Fig. 2 the construction shows the lock 60 formed with the rectangular shoulder E and wedge-shaped ends. Fig. 3 shows the relative features of Fig. 2, with the shoulders omitted.

Fig. 4 is a side view of one of the locks with the wedge-shaped locks, with the ends F 65 overlapping each other, before being placed on the bolt with the ends in a downward position.

In Fig. 5 the wedge-shaped lock is shown with the ends G having the upward curve. 70

In Fig. 6 the lock is wedge-shaped, with the ends H thereof curving within and past each other.

In Fig. 7 the wedge-shaped lock is shown with the end I having the downward curve 75 and the end K curved upwardly and above the end I.

It will be observed that when, through wear and tear, slack is formed on the bolt the spring uncoils with great force, crowding 80 the one wedge-shaped end farther upon the other, thus taking up the slack, and although the lateral strain on the fish-plate is very great when a train passes, yet this will never cause the lock to give way by the wedge ends 85 unsliding, as will occur in spring-locks acting directly against the fish-plate.

The tongs employed to coil the lock are so constructed that they will automatically hold the same on tension until the nut is tightened. 90

Having fully described my invention, what I claim as new, and desire to secure by Letters Patent, is—

A nut-lock consisting of a spring expansion-ring having its opposite inner sides inclined or tapered toward its ends and outer sides forming the wedge-shaped sections B, said ends being coiled and partially overlapped so as to embrace the bolt and in frictional contact at their inclined edges, and the 100 central point of the ring being adapted to rest on the flange of the rail and form a fulcrum, substantially as described.

In testimony whereof I have signed this specification in the presence of two subscribing witnesses.

ARTHUR F. PRITSCHAU.
